Samuel Steelester
ATTORNEY.

UNITED STATES PATENT OFFICE.

JASPER E. FRANCISCO, OF SACRAMENTO, CALIFORNIA.

LUBRICATING SYSTEM FOR MOTORS.

1,208,126.

Specification of Letters Patent. Patented Dec. 12, 1916.

Application filed May 17, 1916. Serial No. 88,657.

To all whom it may concern:

Be it known that I, JASPER E. FRANCISCO, a citizen of the United States, residing at Sacramento, in the county of Sacramento, 5 State of California, have invented certain new and useful Improvements in Lubricating Systems for Motors; and I do declare the following to be a full, clear, and exact description of the same, reference being had 10 to the accompanying drawings, and to the characters of reference marked thereon, which form a part of this application.

This invention relates to improvements in lubricating means or systems for internal 15 combustion motors and is particularly adapted to that type of motor and transmission mechanism used in conjunction with a Ford automobile.

The object of the invention is to produce a 20 lubricating system which will keep the crank case of the motor properly supplied with oil from its front to its rear end irrespective of the angle of inclination which the same may assume when the car in which the engine is 25 installed is traveling in territory having steep grades or the like.

A still further object of the invention is to provide a lubricating system so that good 30 clean oil will be delivered to the crank case and also there will be no possibility of the communication pipe or the outlets for the oil becoming clogged, which would interfere with the circulation of the oil.

A further object of the invention is to produce 35 a simple and inexpensive device and yet one which will be exceedingly effective for the purposes for which it is designed.

These objects I accomplish by means of 40 such structure and relative arrangement of parts as will fully appear by a perusal of the following specification and claims.

In the drawings similar characters of reference indicate corresponding parts in the several views.

45 Figure 1 is a side elevation partly broken out and in section of the motor of a transmission case. Fig. 2 is a top plan view of the removable cover of the transmission case showing my improved lubricant chamber 50 and outlet thereon. Fig. 3 is a sectional view on a line X—X of Fig. 2.

Referring now more particularly to the characters of reference on the drawings, the 55 numeral 1 designates the removable cover on the transmission case 2. In providing my improved lubricating system, I place on the

underside of this cover a receiving receptacle or chamber 3 having an upturned retaining flange 4 at its forward end terminating in a receiving slot or opening 5. An outlet pipe 6 leads from the cover 1 and communicates with the chamber 3. This pipe extends to and communicates with the forward end of the crank case 7 on the underside thereof. The rear end of the chamber 3 is in a lower 60 plane than the upper end as shown in Figs. 1 and 2. When the motor is in operation, the action of the fly wheel 8 in the transmission case 2 tends to throw the lubricating oil which is in the said case 2 against the upper 65 side thereof and a portion of this is splashed and flows through the opening 5 into the chamber 3 where it is retained by means of the flange 4. The chamber 3 being inclined from its forward to its rear end fills with oil, 70 which oil backs up into the pipe 6 and then flows downwardly through said pipe into the crank case 7 through which it passes and any excess overflows back into the case 2 in the usual manner.

75 From the foregoing description it will be apparent that there will always be a continuous circulation of the oil through the pipe 6 and into the case 7. The pipe 6 cannot become clogged for the reason that it 80 communicates with the chamber 3 at approximately the center thereof and any dirt or other deleterious matter which might tend to clog same, settles in the lower end of the receptacle or chamber 3 as at 3^a, only the 85 clean oil passing out through the pipe 6. The pipe 6 is provided with two union joints 6^a and 6^b whereby it may be readily disconnected for any desired purpose, especially for removing the cover 1 to clean out the 90 chamber 3.

95 From the foregoing description it will be readily seen that I have produced such a device as substantially fulfills the object of the invention as set forth herein.

100 While this specification sets forth in detail the present and preferred construction of the device, still in practice such deviations from such detail may be resorted to as do not form a departure from the spirit of 105 the invention, as defined by the appended claims.

Having thus described my invention what I claim as new and useful and desire to secure by Letters Patent is:

110 1. A lubricating system for a motor of the type described comprising the combina-

tion with a removable cover on a transmission case, of a sloping chamber formed on the underside of said cover and provided with an opening, a pipe leading from the cover and communicating with the chamber, such pipe leading to and communicating with the forward end of the crank case of the motor.

2. The combination with a motor and a transmission case, of a chamber formed on the upper side of the transmission case and provided with an opening, and a pipe leading from the chamber and communicating with the forward end of the motor.

3. The combination comprising a motor and transmission case, the top of the transmission case being in a higher plane than the

crank case on the motor, a chamber formed on the top of the transmission case and having an opening and a pipe leading from the chamber and communicating with the crank case.

4. The combination with a motor and a transmission case having a removable cover disposed in sloping relation with respect to the horizontal axis of the crank case, of a chamber formed on the cover and having an opening at its forward end and a pipe leading from the chamber and communicating with the crank case.

In testimony whereof I affix my signature.

JASPER E. FRANCISCO.
